UNITED STATES PATENT OFFICE.

CARL BENSON, OF GARY, INDIANA.

MULTICYLINDER COMPOUND ENGINE.

Application filed August 28, 1922. Serial No. 584,795.

To all whom it may concern:

Be it known that I, CARL BENSON, a citizen of the United States, residing at Gary, in the county of Lake and State of Indiana, 5 have invented certain new and useful Improvements in Multicylinder Compound Engines, of which the following is a specification.

The present invention relates to improvements in multi-cylinder engines and in particular to the compound type embodying high and low pressure cylinders, adapted more especially to be operated by means of steam.

10 15 The primary object of my invention is to provide a simple form of engine of this class designed more particularly for adaptation to the field of automobile construction and these improvements are characterized as 20 to novelty by the provision of a special piston arrangement and driving connection, together with an effective valve mechanism whereby a most efficient power plant is produced for the purpose indicated.

25 30 With the above and other objects in view, the invention consists in certain combinations and arrangements of the parts as will more fully appear as the description proceeds, the novel features thereof being pointed out in the appended claims.

In the drawings:

Figure 1 is a longitudinal sectional view through an engine construction embodying my improvements, showing one of the pistons at the beginning of its power stroke.

35 40 Figure 2 is a view similar to that of Figure 1 with the pistons at an intermediate position and the distribution valve rotated to a position at substantially right angles to that disclosed in Figure 1.

Figure 3 is a sectional view on the plane indicated by the line 3-3 of Figure 1.

45 Figure 4 is a sectional view taken about on the plane indicated by the line 4-4 of Figure 1.

Figure 5 is a sectional view through the valve mechanism on the line 5-5 of Figure 2.

50 Figure 6 is a detail view of the rotating valve member, partly in section so as to show the steam passages and exhaust passage thereof.

Figure 7 is a side elevation of the valve member shown in Figure 6 looking at the

same at right angles to the position shown in Figure 6.

55 Figure 8 is a sectional view through the valve member of Figure 6.

Figure 9 is a detail perspective view of the slide or reversing valve.

60 Figure 10 is a sectional view through the end of the valve chest with the valve member removed and showing more clearly the arrangement of the steam and exhaust passages.

65 Figure 11 is a longitudinal sectional view through a piston unit.

70 Corresponding and like parts are referred to in the following description and indicated in all of the views of the drawings, by like reference characters.

75 Referring to the drawings, the numeral 1 indicates the cylinder casting or block which may have any desired number of cylinders, but as here shown, is provided with a series of such cylinders arranged in a circle, each cylinder unit consisting of a high pressure cylinder 2 and a low pressure cylinder 3.

To this end there is formed in the cylinder casting a central skirt or sleeve 2a of relatively small diameter forming the high pressure cylinder in which is mounted the high pressure piston 4. By reference more particularly to Figure 11, the peculiar piston construction will be clearly understood.

80 85 The high pressure piston 4 is surrounded by a low pressure piston 5, each of these being formed with opposing, elongated extensions 4', 5', having angular extremities 4'', 5'', through which bolts 6 are passed to

90 connect the two pistons into a single unit. It will be noted that a narrow space 7 is left by this construction or arrangement so as to receive the cylinder skirt 2a.

95 The movement of the piston unit is transmitted by means of a common connecting rod 8 to what I will term for the purpose of this description a rocker member 9 of cup-like form, the spindle 10 of which is mounted on a center common to the series of

100 pistons. This spindle, or crank pin, more strictly speaking, is connected by an angle bearing plate 11 with a crank disk 12 secured to a driving shaft 13 projecting through a crank case 14. The connection at each end of the connecting rod 8 is a universal joint connection and it will be apparent that in the rotation of the rocker member 9, its

60

65

75

80

100

105

spindle describes a conical circuit with the crank and shaft and it is understood, of course, that the pistons take steam successively, making a continuous pressure on the 5 circuit of the crank.

Secured to the head of the cylinder casting is a valve chest 15 in which is mounted a rotary valve member 16, shown more clearly in Figures 6 and 7 of the drawings, 10 and motion is transmitted to this member by means of the connection of its stem 17 with a crank plate 18 to which the inner end of the spindle 10 is secured. The extremity of the stem 17 is journaled in a supporting 15 yoke 19 having opposite trunnions 20 bearing in a ring 21, also having opposite trunnions 22 bearing in the rim of the rocker member 9, which thereby is adequately supported to receive the power stresses imparted 20 to it by the pistons.

Reverting to the construction of the valve member 16, reference to Figure 8 will disclose the formation of separate outer, 25 arcuate passages or channels 23 for supplying steam to the low pressure cylinders and separate inner channels 24 for supplying steam to the high pressure cylinders. Each of these channels is provided with an inlet port, designated 23' and 24', respectively, 30 and the former are designed to register with the high pressure cylinder ports 23^a while the latter are arranged to register with the low pressure cylinder ports 24^a, in the cycle of operation of the engine.

35 Mounted upon the rotating valve member 16 is a coacting slide valve 25 which is formed with a low pressure steam passage 26 and an exhaust passage 27, this valve functioning as a reversing valve in the operation 40 of the engine. Sliding movement is imparted to this slide valve by means of a reversing lever 28 which is connected to a thrust collar 29 mounted on the stem extension 30 of the valve member 16, the collar 45 29 having an arm 31 connected by a link 32 to a bell crank 33, the free end of which engages in the recess or notch 34 containing a spring 35, so coacting with the bell crank as to hold the valve member in its operated 50 position.

Speaking with reference to the operation of the slide valve 25 and the position thereof shown in Figure 2, it will be noted that the passage 26 establishes communication 55 through the rotating valve between the high pressure cylinder at one side and the low pressure cylinder at the opposite side, while the passage 27 receives the exhaust from the low pressure cylinder and passes it to an 60 exhaust passage 36 formed in the upper end of the valve stem 17, this last mentioned passage opening laterally of the stem into an annular passage 37 surrounding the stem from which the exhaust passes through a 65 passage or passages 38 to the atmosphere.

While the operation of the engine will probably be apparent from the foregoing description, it will be advantageous to briefly refer to the same at this point.

In the intermediate position occupied by 70 the pistons in Figure 2, steam is entering the valve chamber 15 by means of a conduit 39 from which it passes through the outer steam port 23' into the high pressure passage 23^a and to the high pressure cylinder 2. 75

The opposite cylinder is moving inwardly on its exhaust stroke and the steam from the high pressure cylinder 2, as shown by the arrows, enters the opposite passage 23^a, passing through the outer channel 23 registering therewith into the passage 26 of the slide valve, which passes the steam into the inner low pressure channel 24 to the low pressure cylinder of the opposite cylinder unit. The low pressure cylinder, as shown by the arrows, is exhausting through the valve passages 27, 36, 37 and out to atmosphere by the passage or passages 38. The impetus of the driving piston in this cycle effects a 85 rocking of the member 9 and imparts a rotary motion to the crank disk 12, this rotation in turn shifting the valve so that the next cylinder becomes similarly operative, resulting in a continuous pressure being exerted upon the rocking beam as it moves 95 through its conical circuit above referred to.

In order to equalize the pressure of the steam in the valve chest on the valve, I preferably provide a piston 30^a on the end 100 of the stem 30 which operates in the cylinder head 30^b, the interior of which may be filled with grease or oil.

The high pressure cylinder in this construction is provided with a water outlet 40 and the low pressure cylinder with a corresponding outlet 41. I preferably form the crank case 14 with a depression 14' for oil which is splashed by the operation of the pistons and by the rotation of the crank disk upon the moving parts to provide for effective lubrication of the same. An oil drain 110 14^a is provided, as customary.

I desire it to be understood that as regards details of construction, changes may readily be made without departing from the spirit 115 of the invention and within the scope of the claims hereto appended.

Having thus described my invention, what I claim as new and desire to secure by Letters Patent, is:

1. In a multi-cylinder engine, a plurality of cylinder units, each comprising a high pressure cylinder and a low pressure cylinder and pistons therefore connected for joint operation, a rocker member to which 125 said pistons are connected, a driving shaft, a crank connection between said rocker member and the shaft, a valve chest, and valve means therein operated from the crank connection and adapted to establish 130

communication between the valve chest and the high pressure cylinder of one cylinder unit and between the high pressure cylinder of a second unit and the low pressure cylinder of the first unit mentioned whereby the connected pistons are subjected to high and low fluid pressures.

5. In a multi-cylinder compound engine, a plurality of cylinder units, each comprising a high pressure cylinder and a low pressure cylinder and pistons therefor connected for joint operation, a rocker member to which said pistons are connected, a driving shaft, a crank connection between said rocker member and the shaft, a valve chest, and rotatable valve means in said chest for directing the steam to each cylinder unit successively, said means having ducts establishing communication between the valve 10 chest and the high pressure cylinder of one unit and separate means for simultaneously establishing communication between the high pressure cylinder of another unit and the low pressure cylinder of the first mentioned unit whereby the connected pistons are subjected to high and low fluid pressures.

3. In a multi-cylinder compound engine, a plurality of cylinder units, each comprising a high pressure cylinder and a low pressure cylinder and pistons therefor connected for joint operation, a rocker member to which said pistons are connected, a driving shaft, a crank connection between said rocker member and the shaft, a valve chest, and valve means in said chest comprising a rotatable valve member having ducts for establishing communication with the high pressure cylinder of each 15 unit in succession and a separate duct simultaneously coaxing with the low pressure cylinder, said means including a member having a duct adapted to register with the last mentioned duct to establish communication 20 between the high pressure cylinder of another unit and the low pressure cylinder of the first mentioned unit.

4. In a multi-cylinder compound engine, a plurality of cylinder units, each comprising a high pressure cylinder and a low pressure cylinder and pistons therefor connected for joint operation, a rocker member to which said pistons are connected, a driving shaft, a crank connection between said 25 rocker member and the shaft, a valve chest, and valve means in said chest comprising a rotatable valve member operated from the crank connection aforesaid and having a duct establishing communication between 30 the chest and the cylinder units in succession and a separate valve member operated with the first mentioned member having a coaxing duct to establish communication between the cylinder units as an incident to the operation of the first mentioned valve

member whereby the connected pistons are subjected to high and low fluid pressures.

5. In a multi-cylinder compound engine, a plurality of cylinder units, each comprising a high pressure cylinder and a low pressure cylinder and pistons therefor connected for joint operation, a rocker member to which said pistons are connected, a driving shaft, a crank connection between said rocker member and the shaft, a valve chest, and valve means in said chest comprising a rotatable valve member having ducts adapted to register with the respective cylinder ports and a second valve member slidably mounted on the first valve member and having coaxing ducts communicating with the cylinder units and disposed to feed the exhaust from the high pressure cylinder of one unit into the low pressure cylinder of another unit.

6. In a multi-cylinder compound engine, a plurality of cylinder units arranged about a common center, each comprising a high pressure cylinder and a low pressure cylinder and a piston unit in each connected for joint operation, a rocker member to which said piston units are connected, a driving shaft, a crank connection between the rocker member and the shaft, a valve chest, valve means therein including a rotatable valve member having a shaft arranged centrally of the cylinder units operated from the crank connection aforesaid and a slideable valve member mounted on the rotatable valve member for rotation therewith, and means for shifting said slideable valve member relative to the rotatable valve member.

7. In a multi-cylinder compound engine, a plurality of cylinder units arranged about a common center, each comprising a high pressure cylinder and a low pressure cylinder and a piston unit in each connected for joint operation, a rocker member to which said piston units are connected, a driving shaft, a crank connection between said rocker member and the shaft, a valve chest, valve means therein including a rotatable valve member having a stem operatively connected with the crank connection aforesaid, said stem having formed therein an exhaust passage, said rotatable member having high and low pressure steam passages therethrough to communicate with each unit, and shiftable reversing means coaxing with the rotatable member and having ducts therein adapted to coat with the passages of the rotatable member to establish communication between the cylinder units and exhaust passage aforesaid.

8. In a multi-cylinder engine, a plurality of cylinder units, each comprising a high pressure cylinder and a low pressure cylinder and pistons therefor connected for joint operation, a rocker member to which said pistons are connected, a driving shaft, a

spindle on which said rocker member is mounted, a crank disk upon the driving shaft to which said spindle is eccentrically connected at one end, a yoke member to which the other end is universally connected, and valve means for the cylinders including independently operable superposed valve members, one of which is provided with an operating shaft connected with the spindle 10 aforesaid.

9. In a multi-cylinder compound engine, a plurality of cylinder units, each comprising a high pressure cylinder and a low pressure cylinder and pistons therefor, a rocker member to which said pistons are connected, a driving shaft with which said rocker member is operatively connected, a valve chest, and valve means therein comprising a rotatable valve member having ports to intro- 15

duce high and low pressure fluid to each unit and a coacting slidable valve member, said slidable valve member being rotatable with and shiftable with respect to the rotatable valve member to effect reverse movement. 20

10. The combination with a low pressure cylinder and a high pressure cylinder therein, of a piston unit including an annular low pressure piston and a high pressure piston surrounded by the low pressure piston, a skirt extension from each piston connected to each other and provided with detachable connecting means to permit separate removal of the pistons, and a connecting rod pivoted to the high pressure piston and disposed within its extension. 25

In testimony whereof I affix my signature.
CARL BENSON. 30 35
